UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR PIN.

Application filed May 12, 1920. Serial No. 380,826.

This invention relates to pins for supporting insulators for various electrical conductors, and has for its object the provision of devices of the class named which shall be of improved construction and operation.

The invention is exemplified in the combination and arrangement of parts shown in the accompanying drawings and described in the following specification, and it is more particularly pointed out in the appended claim.

In the drawings—

Fig. 1 is an elevation of one embodiment of the invention with parts in section;

Fig. 2 is a horizontal section on line 2—2 of Fig. 1;

Fig. 3 is a vertical section on line 3—3 of Fig. 2;

Fig. 4 is an elevation with parts in section of a slightly different form of the invention.

Insulators for electrical conductors are supported in a variety of ways, one of the common means being by the use of pins carried by the supporting structure and bearing the insulator fitted over the end thereof. Such pins are used for supporting insulators on metal and wooden arms and pole tops and also on various constructions other than regular line wire supports. A pin to meet the requirements to which it is subjected must have the necessary mechanical strength to withstand the stresses brought upon it and should not materially lower the flashover voltage of the insulator or otherwise diminish the electrical efficiency of the insulator. The cost of manufacture should be kept as low as possible and the pin should provide the required strength without setting up undue stress in the fragile material of the insulator which it carries. The pin should also be adaptable to various conditions which arise in line construction and other electrical installations where insulators are used, and it is also desirable that the pins should be so designed that a large variety can be made from as small a variety of stock as possible.

From the various embodiments of the invention shown in the drawings, it will be apparent that the small body diameter of pins constructed in accordance with this invention permits developing the maximum flashover voltage value of the insulator since

the small diameter of the pin body keeps the outer surface of the body at a maximum distance from the lower edge of the insulator itself. It will also be seen that the supporting base and the body portion of the insulator are made in separate parts which permits the use of a base having sufficient area so that the cross-arm upon which the base rests will not be crushed under bending moment. The construction permits of a balanced arrangement and at the same time does not sacrifice the electrical properties of the insulator. In pins having a small base formed integrally with the pin, the bending moment upon the pin forces the edge of the base into contact with the upper face of the supporting structure so that where the structure is made of wood, the fibres are crushed at the edge of the base, permitting the pin to lean to one side and loosening the connection with the support. It is impractical to form a pin with an integral base of sufficient area to overcome this difficulty, for the reason that if the pin is cut from a piece of stock of large diameter the waste is too great to justify a sufficient expanse of base, and if it is undertaken to upset or swage a smaller piece of stock to form the base, it is impossible to expand the material a sufficient amount to give a base of the required extent. Such operation also tends to form laps or flaws in the metal. Where the base is formed separately from the pin and is provided with means to hold the two rigidly together, when the pin is installed, the base may be made of any desired extent and shape and pins may be standardized so that the same pins may be used with a large variety of supporting bases. A pin may be secured to the base by means of a tapered end fitting in a tapered socket and the taper may be so proportioned that the pins may be readily made with a swaging-machine from straight-bar stock without the loss of material. No finishing operation is necessary other than the swaging process in order to obtain a good fit for the base. The taper should be such that the pin will not tend to lift out of the base when a bending moment is applied, and at the same time the taper should preferably be such that the pin will not bend in the small sections, the smaller portion of the pin being

reinforced by the base. When the base and body are assembled they are held together so that they will work as a unitary structure and the main body of the pin may be made 5 in straight section or given a taper which will give uniform strength for the bending moment, or it may be made in stepped diameters, if desired.

The insulator may be secured to the pin in 10 a large variety of ways, depending upon conditions. In some cases a lead tip may be cast or pressed on the pin which will form a cushion between the hard metal and the porcelain. The upper portion of the pin 15 may, under some conditions, be provided with a roughened surface, or with resilient flanges or projections, to reduce the danger of cracking the insulator under expansion and contraction of temperature changes.

20 Another method of securing the insulator to the top of the pin is to provide the end of the pin with large or small threads which can be adapted to a thimble of sheet material threaded into the insulator. In this construction, the threaded parts may be cone-shaped and the insulator may be tightened down firmly and afterwards the wire groove in the insulator may be properly aligned by turning the pin relative to its supporting 25 base. The thimbles, however, instead of being cone shaped may be cylindrical so that they can be turned upon the pins to align the wire grooves without loosening the insulator on the pin. Where this arrangement is 30 made, the pin can be rigidly attached to the supporting base. Under most conditions, however, the pin and base will be separable which will permit combinations of various forms of pins with different kinds of bases 35 so that the proper arrangement may be secured for a large variety of conditions.

In Fig. 1 the reference character 1 designates the main body portion of an insulator pin which is preferably made of metal and 40 which, as shown, is provided with screw threads 2 at its upper end for receiving the insulator. The lower end of the pin is tapered, as shown at 3, and is provided with an extension 4 which passes through an 45 opening in the cross-arm or other supporting structure and which is threaded at its extremity to receive a nut 5 and a washer 6 by which the pin is securely attached to the cross-arm. A socket member 7 is provided 50 with a tapered socket for receiving the tapered portion 3 of the pin and the member 7 rests upon an extended base 8 which supports the pin upon the cross-arm. The portion of the pin extending through the socket member 7 and base 8 is threaded, as shown 55 at 9, to receive a nut 10 by which the pin is tightly drawn into the socket 7 and by which the pin and the socket and the base 8 are fastened securely together so that when assembled they operate as one piece. The up-

per end of the opening in the cross-arm for receiving the extension 4 is preferably counter-bored to provide space for the nut 10. The base member 8 is shaped to conform to the upper face of the cross-arm upon which 70 the pin is supported and extends along the length of the cross-arm a sufficient distance to distribute the force to which it is subjected over an extended area. In the usual construction the cross-arms for supporting the 75 pins extend transversely of the direction of the line and the greatest stress to which the pins are subjected is in a direction transverse to the direction of the line which consequently is in the direction of the length of 80 the cross-arm. By extending the base member 8 along the cross-arm it is therefore possible to secure a large supporting area to resist the lateral pressure upon the conductor. It is desirable that there shall be no 85 sudden breaking in the pressure exerted by the base 8 upon the cross-arm such as would occur at the edge of a flat piece of metal. Such a break in the pressure would tend to cut or injure the fibers of the wood at the 90 edge of the metal and thus impair the efficiency of the pin. This is especially true for base members of small extent, and the fact that applicant's member is elongated and covers a considerable area helps to overcome this defect to a great extent. The difficulty is further overcome by slightly curving the base member 8 upwardly at its ends, as shown at 11 in Fig. 3. The curve 11 is made comparatively long and gradual and so overcomes and sudden break in the pressure brought to bear by the base 8 on the upper 100 face of the cross-arm.

By providing the pin with a separately formed base 8, it is possible to roll or stamp 105 the base from ordinary stock, and because it is formed independently of the pin 1, it may be made of any extent desired. The socket member 7 and the pin 3 may also be formed by simple manufacturing processes, such as 110 swaging, so that the entire construction may be cheaply produced and yet when it is assembled, it acts as a single unit and constitutes an efficient construction.

The form of the invention shown in Fig. 115 4 is similar to that of Fig. 1 with the exception that the nut 10 in Fig. 1 is dispensed with and the base member 8 is threaded to receive a threaded portion 12 on the pin 1. With this construction, it is not necessary to 120 counter-bore the opening through the cross-arm and the pin and supporting base are tightly clamped together by threading the lower portion of the pin into the opening in 125 the base 8.

I claim:

An insulator pin comprising an elongated pin body having a tapered portion adjacent the lower end thereof, a laterally extending 130 separately formed base member having an

opening therein for receiving said pin body, a separately formed socket member having a

tapered socket for receiving the tapered portion of said pin body, a threaded member for securing said pin body, base and socket member in fixed relation to one another, and means for holding said members when as-

sembled in position on a supporting structure.

In testimony whereof I have signed my ¹⁰ name to this specification on this 7th day of May A. D. 1920.

ARTHUR O. AUSTIN.
